UNITED STATES PATENT OFFICE.

ALVIN F. NYE, OF ROCHESTER, NEW YORK, ASSIGNEE TO FLI-BAC SCREEN CORPORATION, OF ROCHESTER, NEW YORK, A CORPORATION OF NEW YORK.

WINDOW SCREEN.

Application filed May 14, 1921, Serial No. 469,503 Renewed April 1, 1927.

This invention has to do with window screens and relates more particularly to the construction of binding strips or rails for the same and the means for connecting the latter to the screen material, the chief object of the invention being to provide a simple, practical and inexpensive construction affording a strong and durable rail with an efficient and convenient means for securely attaching the screen material thereto. To these and other ends the invention consists in certain improvements and combinations of parts, all as will be hereinafter more fully described, the novel features being pointed out in the claims at the end of the specification.

In the drawings:

Figure 1 is a sectional elevation of a window casing as viewed from the inside with the invention applied thereto;

Figure 2 is an enlarged section on the line 2^a—2^a of Figure 1 showing the construction of the binding strip or rail and the connection of the latter with the screen material.

Similar reference characters throughout the several views indicate the same parts.

The present invention provides an advantageous binding strip or rail for a window screen, in the present embodiment showing the same as applied to a window screen of the type employing a flexible wire cloth or mosquito netting wound on a spring roller journaled in the window casing. Referring to Figure 1 of the drawings, which illustrates such an application of the invention, there is shown at 5 a window casing with a sill 6, 7 indicating the stops or guide strips for the outer window sash. Fixed on the latter are guides 8 preferably in the form of sheet metal channel members having inner and outer flanges 9 and 10 respectively between which the screen material slides. The screen is wound on a spring actuated roller 11 journaled at its ends in bearings 12 on the casing, these parts being preferably located in a housing 13 at the top of the casing, the roller turning to wind or unwind the screen material as the latter is raised or lowered by means of a binding strip or bottom rail secured to its lower end.

The wire cloth or netting of which such screens are generally made is relatively stiff, and as it must be maintained in close fitting engagement with its guides on the window casing to prevent openings through which insects might pass, the screen material offers

a frictional resistance against sliding movement and requires a substantial binding strip or rail at its lower end carrying the handles or other means by which the screen is moved, which rail must be capable of close engagement throughout its length with the window shelf and moreover must be securely connected with the screen material to prevent the latter from unraveling at its edge or otherwise becoming torn or disconnected from the rail. To this end there is preferably provided a rail indicated generally at 15 as formed from a single strip of sheet metal, of substantially channel shape, having an intermediate flat portion 16 adapted for close engagement with the window sill, with angularly extending flanges 17 and 18 at its sides. The flanges extend substantially parallel with each other and are preferably corrugated as at 19 adjacent the intermediate portion 16 to provide a somewhat resilient connection to absorb the shock of impact against the window sill, and to strengthen and stiffen the same against lateral binding. As shown in the drawing, the inner flange 17 preferably has its upper portion curved toward the other flange 18 and bent sharply upon itself as at 20 to provide a projecting ridge portion, the flange being continued beyond such portion as at 21 for engagement with the other flange and these engaging portions may be securely fastened together if desired, in any suitable manner. The other flange 18 has its marginal portion curved as at 22 to closely embrace the sides of the ridge portion 20 and its edge is turned inwardly of the rail as at 23. These embracing marginal portions of the flanges are preferably so formed as to leave a slight space therebetween and the edge 23 is externally exposed as shown in Figure 2.

The screen material has its lower end inserted between the embracing portions of the flanges, being bent twice upon itself to extend around or embrace the ridge portion 20 and also the edge portion 23 of the respective flanges, the material being preferably first bent into this form and slipped into position from one end of the rail during assembly. The sharply bent portions of the screen or netting are held in such shape by the embracing portions of the flanges and effectively bind against the latter so that the screen is securely held against detachment from the rail. The inner flange of the latter is pro-

vided with handles 24 for moving the same.

As apparent from the construction shown and described, the rail is simple and practical in character, being preferably formed 5 from a single strip of sheet metal which is readily rolled into shape. The rail has sufficient width in cooperation with the screen guides to maintain it in proper alignment during movement and is adapted to closely 10 engage a window sill and close the window tightly and the character of construction adopted affords a strong and durable rail capable of withstanding any force necessary to be applied. Combined with this 15 advantageous construction of the rail is the effective connection described between the latter and the screen material whereby the material is readily attached during assembly and securely engaged and held by the rail at all 20 points over the width of the material and for a sufficient distance from its end as to obviate any danger of its tearing or pulling away from the rail. In addition to these 25 practical advantages, the rail and its method of connection with the screen present a neat and attractive appearance.

I claim as my invention:

1. A binding rail for a window screen comprising an integrally formed substantially 30 channel shaped bottom rail having its intermediate portion at the bottom for contact with the window sill and upwardly extending flanges at the sides thereof, an upper portion on one of said flanges bent downwardly 35 on itself to form an upwardly projecting ridge and a downturned edge for attachment

to the other flange, and an upper portion on the other of said flanges bent over and closely embracing said ridge with a downwardly extending edge adapted to hold a screen material between said ridge and said embracing portion. 40

2. A binding rail for a window screen comprising an integrally formed substantially channel shaped rail having its intermediate 45 portion disposed for contact with the window casing with side flanges extending angularly therefrom and provided with a plurality of corrugations affording resilient connection with said intermediate rail portion, a 50 projecting ridge portion on one of said flanges, and a marginal portion on the other of said flanges closely embracing the sides of said ridge portion with an externally disposed edge portion and adapted to hold a screen material between said ridge and said 55 embracing portion.

3. A binding rail for a rolling window screen formed integrally from a single sheet metal strip shaped to present an intermediate 60 portion for engagement with a window casing with angularly extending flanges at the sides thereof, one of said flanges having its margin curved back upon itself to provide a ridge portion and to engage with said other 65 flange, said other flange having its margin curved to closely embrace said ridge portion with its edge portion extending inwardly of the rail, and being adapted to retain a screen material between said curved margin and 70 said ridge portion, and a handle on said rail.

ALVIN F. NYE.
